UNITED STATES PATENT OFFICE.

ALEXANDRE LAMBLIN, OF PARIS, FRANCE.

FEEDING DEVICE FOR COOLING RADIATORS.

Application filed January 29, 1924, Serial No. 639,223, and in France February 27, 1923.

Feeders are already known, that is to say large containers mounted in the cooling water pipes of a thermal motor and ensuring the supply of water to these pipes and the radiators which are connected thereto. The steam formed in the pipes is drawn into the radiators, when the motor becomes abnormally heated, collects in these feeders and is partially condensed therein by the external cooling action or can escape into the outer air.

The feeder arrangements hitherto known however do not afford a sufficiently intense cooling and do not permit of a sufficiently rapid condensation of the steam.

The present invention relates to a special arrangement of feeder which avoids the preceding disadvantages. This arrangement is characterized substantially by a container of suitable surface and volume connected to the cooling water system of the motor, this container being combined with a sleeve for the admission of air to the carburetter, so that the cold air drawn into said sleeve ensures an intense cooling of the elements of this container, increasing consequently, the condensation of the steam which may collect in this container and ensures the heating up of the carburetter by the heating of the air admitted thereto.

Various arrangements according to this invention are shewn by way of example in the accompanying drawings in which:

Figure 1 is a section of an arrangement according to this invention, taken on the line 1—1 of Figure 2.

Figure 2 is a longitudinal section of the preceding arrangement in a vertical plane on the line 2—2 of Figure 1.

Figure 3 is a section of this arrangement in a horizontal plane on the line 3—3 of Figure 2.

Figure 4 is a cross section of a modification of the invention in a vertical plane at right angles to the axis of the air sleeve.

Figure 5 is a cross section of a second modification.

Figure 6 is a cross sectional view of another modification. Figure 7 is a longitudinal section on the line 7—7 of Figure 6 of the same modification.

Figures 8 and 9 show a fourth modification.

Figures 10 and 11 are two diagrammatic

elevations of systems of pipes for the cooling water for thermal motors.

Figure 12 is a side elevational view of the carburetter and air connection thereto from an auxiliary reservoir of the type illustrated in Figure 6.

The arrangement shewn in Figures 1 to 3 comprises a reservoir 1 and a sleeve 5 for admitting air to the carburetter.

The reservoir 1 is provided with a filling plug 2 and is connected by two pipes 3 to the water jacket of the motor. Baffles 4 fixed to the interior of the reservoir, guide the currents of hot water arriving from the motor.

The air admission sleeve 5 is surrounded by a jacket or casing 6 which thus forms 70 around the periphery of this sleeve a free space 7 communicating freely on the one hand by the openings 8 with the lower part of the reservoir 1 and on the other hand with the water jackets by the connection 9. 75

The pipes 10, of very elongated cross section (see Figure 3) and provided with cooling gills 11, connect the upper part and the lower part of the free space 7 passing right through the air sleeve 5.

The arrangement above described works in the following manner:

When the motor becomes heated abnormally, a certain quantity of cooling water vaporizes. The level of this water sinks 85 gradually in the reservoir and when this reservoir is entirely empty, the level of the water drops below the air sleeve 5. At this moment the pipes 10 and the free space 7 become completely filled with steam and are 90 intensely cooled by the current of cold air drawn in along 14 into the air sleeve. They thus constitute a condenser of large cooling surface which ensures rapid condensation of the steam formed in the pipes.

This intense cooling action produced by this condenser counterbalances the abnormal heating of the motor.

While the motor is working normally, the hot water drawn in by the pump passes into 100 the reservoir 1 by the pipes 3. These two currents of hot water are diverted downwards by the baffles 4, and pass through the openings 8, then into the free space 7, through the pipes 10 and escape through the 105 pipe 9.

The air drawn into the air sleeve 5 in the direction shewn by the straight arrows 14

plays over the lateral surfaces of the pipes 10 and the gills 11 fixed on these pipes.

This ensures, while the motor is running normally, both a certain cooling of the water which passes through the reservoir 1, which facilitates the work of the radiators, and a heating up of the air admitted to the carburetters and consequently the heating of the carburetters themselves.

10 The particular arrangement of the reservoir 1 relatively to the air sleeve 5, this reservoir being arranged above the air sleeve and the pipes 10, has the advantage that, when the motor is running normally, the pipes 10 are constantly filled with hot water and thus constantly ensure the heating of the carburetter.

15 The arrangement shewn in Figures 1 to 3 has been described by way of example only and may comprise numerous modifications to which this invention extends.

20 In particular, instead of arranging the reservoir 1 above the air sleeve, the pipes 10 prolonging the lower part of this reservoir 25 into the interior itself of the air sleeve, I may on the contrary arrange the reservoir below the air sleeve 5. In this case, the pipes 10 prolong the upper part of the reservoir through the air sleeve 5.

25 30 The circulation of hot water in this arrangement is exactly similar to that in the arrangement shewn in Figures 1 to 3. This circulation of the water is indicated by the arrows in Figure 4.

35 40 As soon as the level of the water in consequence of excessive wear or heating of the motor, sinks in the pipes 10, these pipes, intensely cooled by the air drawn into the sleeve 5, at once act as a condenser and condense the steam which has collected in the apparatus.

45 These pipes continue also to heat up the air admitted to the carburetter, by giving up to this air a fraction of the heat still contained in the hot water circulating in these pipes.

50 55 It has been supposed in the preceding examples (i. e. Figures 1 to 4) that the reservoir 1 is placed directly around the air sleeve 5. I may obviously however, place this reservoir slightly above the air sleeve as shewn in Figure 5, this reservoir then communicating with the free space 7 by a pipe 40.

55 60 This arrangement works in exactly the same way as the preceding ones as soon as the level of the water sinks below the air sleeve 5, all the parts 10, 11 act as condensers according to the invention.

60 65 I may also, as shewn in Figures 6 and 7 place the reservoir 1 inside the air sleeve, this reservoir and this air sleeve forming a single element.

65 In this case, the general outline of the reservoir 20 conforms to the general outline

of the air sleeve. This reservoir is traversed along its axis by a pipe 21 for the passage of air.

The air sleeve 5 is surrounded as formerly by a jacket or casing 6 forming around the periphery of this sleeve a free space 7 divided into two parts by longitudinal partitions 23. This free space communicates with the reservoir 20 by radial pipes 22 having gills 24.

75 The hot water coming from the motor by the two pipes 3 fills the upper part of the free space 7, passes through the radial pipes 22 into the central reservoir 20, passes on through another series of radial pipes 22, collects in the lower part of the free space 7 and flows through the pipe 9 into the cooling water pipes.

80 The air drawn in through the air sleeve 5 in the direction indicated by the arrows 14, plays over the radial pipes 22, then gills 24, the outer walls of the central reservoir 20 and the walls of this reservoir which formed the central passage 21.

I thus obtain a continuous heating of the air admitted to the carburetter, and an intense condensation of the steam as soon as the level of the water sinks in the apparatus either in consequence of being used up or excessive heating of the motor.

85 90 In the arrangement above described (see Figures 6 and 7) the central reservoir 20, the radial pipes 22, and the free space 7 constitute a series of elements communicating with each other and containing a large 100 reserve of water which permits of the automatic replenishment of the losses in the pipes and radiators. Consequently in this arrangement the feeder, that is to say the container connected to the cooling water 105 pipes of the motor and combined with the air sleeve, is in fact constituted, not only by the central reservoir 20, but also by all the preceding elements 20, 22, 7.

I can therefore constitute this feeder by 110 dispensing with this central reservoir 20 and replacing it by bundles of tubes 30 having gills 31 (see Figures 8 and 9) passing from side to side of the air sleeve 5 and connecting together the upper and lower parts 115 of the free space 7, separating the partitions 23, on condition only of providing a sufficient number of these pipes and giving them a suitable surface and volume.

120 The hot water comes in from the motor at 3, fills the upper part of the free space 7, passes through the vertical pipes 30, fills the lower part of the free space 7 and rejoins the general system of pipes by the connection 9.

125 The air circulates as before in the direction of the arrows 14.

130 This arrangement works as a condenser in a manner exactly similar to the arrangement shewn in Figures 6 and 7. It will

be easily understood that by making the pipes 30 of sufficient diameter and by providing a large number of these pipes inside the air sleeve 7, a feeder of large capacity 5 will be obtained, containing a large quantity of water which automatically makes up the losses from the pipes and radiators.

The arrangement shown in Figure 9 also 10 efficiently realizes the essential characteristic of the invention, that is to say the combination of a feeder and an air sleeve, the whole thus constituted acting as a condenser for steam.

I may obviously mount the above described arrangements in numerous different 15 ways on the general cooling pipes of the motor.

For example (Figure 10) an arrangement 20 1, 2, 5, 10 according to that shewn in Figures 1 to 3, may be realized on the one hand by the pipe 3 with the cooling jacket 35 of the motor, and on the other hand by the pipe 9, with a radiator 36, a rotary pump 37 draws in through the pipe 38 the 25 cooled water into the radiator 36 and forces this water through the pipe 39 into the cooling jacket 35 of the motor.

I may also place an arrangement 1, 2, 3, 5, 10 according to that shewn in Figure 4, 30 in the V formed by the cylinders (see Figure 11). This arrangement is connected by two pipes 3 to the cooling jackets 35, of these cylinders and by pipes 9 to the radiators 36.

The rotary pump 37 draws in by the pipes 38 the cooled water from the two radiators 36 and forces this water through the pipes 39 into the jackets 35 of the motors. 35

It will be seen that these various ways of mounting the whole constituted by the feeder and the air sleeve is arranged in 40 order with respect to the rotary pump.

What I claim is:

1. In a thermal motor installation, the combination of a motor having a cooling jacket, a radiator, connections between the jacket and the radiator, a sleeve for admitting air to the carburetor, a water reservoir separate from the radiator and arranged within said sleeve, and a plurality of cooling elements connecting the water reservoir to the upper part of said connections and traversing said air admission sleeve, whereby air drawn by the motor into said sleeve sweeps said reservoir and said elements. 45 50

2. In a thermal motor installation, the combination of a motor having a cooling jacket, a radiator, connections between the jacket and the radiator, a sleeve for admitting air to the carburetor, a water reservoir, a casing enclosing said sleeve and forming 55 60 a free space between the casing and sleeve, and pipes connecting the reservoir to said free space and to said connections.

In testimony whereof I affix my signature.

ALEXANDRE LAMBLIN.
